CLAIM

The ornamental design for a vessel for plant-based milk maker, as shown and described.

DESCRIPTION

FIG. 1 is a perspective view of a vessel for plant-based milk maker;

FIG. 2 is a front elevation view thereof;

FIG. 3 is a rear elevation view thereof;

FIG. 4 is a side view thereof;

FIG. 5 is an opposing side view of FIG. 4;

FIG. 6 is a top plan view thereof; and,

FIG. 7 is a bottom plan view thereof.

The portions of the vessel for plant-based milk maker shown in broken lines form no part of the claimed design.
